CLAIM

The ornamental design for a hair drying hood for use with upright hair dryers, as shown and described.

DESCRIPTION

FIG. 1 is a front elevational view of a hair drying hood for use with upright hair dryers showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a bottom, front and right side perspective view showing the design configured for use.

The broken lines showing a human form and a hair dryer in FIG. 7 are for illustrative purposes only and form no part of the claimed design.
